UNITED STATES PATENT OFFICE

DOUGLAS J. MARTIN, OF NEW YORK, N. Y., ASSIGNOR TO MARTIN MOTORS, INC., OF NEW YORK, N. Y., A CORPORATION OF DELAWARE

INTERNAL-COMBUSTION ENGINE

Application filed November 16, 1927. Serial No. 233,670.

This invention relates to internal combustion engines, the broad object of the invention being to provide means in the form of an auxiliary piston co-operating with the working piston to maintain compression or increase compression within the cylinder while the working piston is passing over dead center so that there is no loss of compression, and the firing or ignition takes place when the crank arm, to which the working piston is connected, is in the most effective position.

A further object is to provide an engine of the character stated in which the crank arm of the drive shaft to which the working piston is connected is disposed within a sector centering on 90° to an eccentric on the crank shaft, the strap of said eccentric being to the auxiliary piston whereby the action of the eccentric and the auxiliary piston has a lag behind the movement of the working piston.

This engine is adapted for high or low speeds and has many advantages over the other types of engine, all of which will be more fully hereinafter described and pointed out in the claim.

In the accompanying drawings—

Figure 1 is a view in longitudinal section of my improved engine, showing the pistons in approximate position for ignition of the mixture;

Figure 2 is a fragmentary view taken at right angles to Figure 1 through the crank case and a portion of the engine;

Figures 3, 4, 5 and 6 are diagrammatic views showing the various positions of the pistons in the cylinder during the power and suction stroke;

Figure 7 is a diagram illustrating the movements and operation of the pistons.

I shall first describe the engine illustrated and later set forth the operation and advantages attained by the engine.

1 represents an engine cylinder having a

closed head 2 and at its lower end secured to a crank case 3 in which a crank shaft 4 is mounted. For convenience of description I shall refer to the "upper" and "lower" ends of the engine but it is of course to be understood that the engine may function in other positions than in a vertical one and that this language is employed for convenience in describing the engine.

5 and 6 represent inlet and exhaust valves in head 2 and 7 is a spark plug or other means for ignition. In the casing 1 a working piston 8 is provided and connected by a connecting rod or link 9 with a crank arm 10 on shaft 4.

55 This working piston 8 reciprocates within an auxiliary piston 11, the latter reciprocating freely in the cylinder 1. The auxiliary piston 11 is connected at its lower end, and at opposite sides, by links or connecting rods 12 with eccentric straps 13 on eccentrics 14 on the crank shaft 4.

60 This working piston 8 reciprocates within an auxiliary piston 11, the latter reciprocating freely in the cylinder 1. The auxiliary piston 11 is connected at its lower end, and at opposite sides, by links or connecting rods 12 with eccentric straps 13 on eccentrics 14 on the crank shaft 4.

65 The crank arm 10 and the eccentrics 14 are disposed within a sector centering on an angle of approximately 90° to each other, and this is an important phase of my invention that will hereinafter be enlarged upon.

70 The arrangement of pistons and their mountings in the cylinder is capable of modification, but I have illustrated the auxiliary piston as having an annular chamber 15 externally thereof in which inlet and exhaust openings 16 and 17 are provided for the passage of a cooling medium.

75 Furthermore, I may provide around the auxiliary piston a spiral or other web 17' to strengthen the piston and guide the same in the cylinder.

80 The lower end of the auxiliary piston is preferably provided with one or more keyways 18 receiving keys 19 in the cylinder 1 so as to prevent rotary movement of the auxiliary piston 11.

85 It is to be understood that a preferable arrangement is such that the areas of the up-

90

per ends of the working piston 8 and the auxiliary piston 11 are the same, but this is of course capable of modification, in accordance with the results desired.

5 In this particular case I desire that the auxiliary piston may be either of the same area as the working piston or has a movement which will displace a volume equal to the displacement of the working piston end, so that 10 as the working piston moves past dead center, which is a downward movement, the auxiliary piston will move upwardly and maintain a volumetric balance. If the auxiliary piston displaces a larger volume than the working 15 piston the result will be a super-compression or post-compression which may also be accomplished by a greater movement of the auxiliary piston and this variation in movement is of course controlled by the throw of the eccentric.

To explain the operation of the engine, attention is called to the diagram Figure 7 and also to Figures 3, 4, 5 and 6 which illustrate different positions of the pistons.

25 In the diagram (Figure 7) the bisected circle at the left indicates a complete revolution of the crank shaft, the capital letters indicating the sectors of movement of the crank arm 10, and the small letters the movement of the eccentric. The horizontal lines extending to the right of the circular diagram indicate the linear movement of the working piston in a complete reciprocation and the small diagram at the upper, right-hand portion of Figure 35 7 illustrates the linear movement of the auxiliary piston registering with a small circular diagram indicating the movement of the eccentric.

Also at the central portion of the right-hand circular diagram (Figure 7) the horizontal lines indicate the linear movement of the auxiliary piston as brought about by the turning movement of the eccentric.

Figure 3 illustrates the working piston at 45 the extreme of its upper movement with the crank arm at dead center, and it shows when in this position that the auxiliary piston is substantially parallel to the working face of the working piston.

50 Figure 4 illustrates the approximate firing position, and it will be noted that as the crank arm passes over dead center the working piston 8 moves downwardly at the same time the auxiliary piston moves upwardly, thus 55 maintaining a volumetric balance in the cylinder.

Figure 5 shows the working piston 8 moving downwardly on its power stroke and it will be noted that during a portion of the downward movement of the working piston the auxiliary piston moves upwardly and then follows downwardly with the stroke of the working piston.

However, it will be noted that the linear 65 movement of the auxiliary piston is very short

as compared with the movement of the working piston due of course to the throw of the eccentric as compared with the throw of the crank arm, but these movements of the working and auxiliary pistons are exactly timed in accordance with the angular position of the crank arm relative to the eccentric which will now be explained, reference being had more particularly to the diagram in Figure 7.

The circle indicating the movement of the crank arm and eccentric in Figure 7 is, for convenience of description, divided into sectors of twenty-two and a half degrees each, and the diagram indicates an engine with a pressure balanced through twenty-two and a half degrees.

While the working piston crank turns through the first sector A, the eccentric shown at a 90° lag also turns through a sector of the same size, indicated by a . The diagram shows that the working piston falls a distance, indicated by A' , and the auxiliary piston rises a distance, indicated by a' . A' and a' are equal and the eccentric circuit may be so designed that this equal fall and rise will hold good to any desired point of balance.

At top dead center, the working piston and the auxiliary piston are side by side. As the working piston falls through the distance indicated by A' , the auxiliary piston rises through an equal distance, indicated by the character a' .

As the crank arm turns through the sector B the working piston falls a distance, indicated by B' , and the eccentric turns through the sector b and rises a much lesser distance than the working piston, as indicated at b' .

These relative movements can be followed on the diagram through the medium of the letters, the capital letters indicating the sectors through which the crank arm moves and the small letters indicate the sectors through which the eccentric moves, the primed capital letters indicating the linear movement of the working piston and the primed small letters indicating the linear movement of the auxiliary piston.

Furthermore, this diagram to the extreme right indicates a complete movement downwardly of the working piston, indicated by the captions and by the lines registering with the other lines of the diagram. The small space at the upper portion of this column above referred to indicates the space of time of the volumetric balance and ignition then following is expansion, continuing through the measures B, C, D, E and F and exhaust through G' , H' .

It is of course to be understood that the timing of the exhaust may be varied so that it may be lengthened or shortened, but in any event this exhaust takes place while this piston is at or near its lowest sector.

The capital letters I', J', K', L', M', N', O', P', indicate the movement of the piston

on its scavenging stroke as well as on its compression stroke, and this complete reciprocation is of course repeated in a four-cycle engine to draw in the charge and compress it, 5 as above explained.

In the above description of my invention I apply the term "auxiliary piston" to the part 11 and as this piston functions as a compression member, forming a part affixed to a tube 10 or sleeve it may also be termed a "compression piston", and these terms are used indiscriminately as the part 11 is in reality both a piston, a sleeve and a compression member.

An engine such as above described and operated in the manner stated has many advantages some which may be enumerated as follows:

There will be no loss of compression while the piston is passing over dead center.

20 The compression may either be maintained or increased to super-compression or post-compression in accordance with the throw of the eccentric.

The work of compression and super-compression is divided between the crank arm 25 and the eccentrics, the working piston and the auxiliary piston both moving toward the head of the cylinder for compression and for maintenance of compression. This enables 30 the cutting down of the weight of the individual parts.

The working piston moves up rapidly and attains the first stage of compression and when it has arrived at a certain pressure the 35 auxiliary piston or compression piston moves up and increases this pressure to any desired amount in accordance with the movements imparted to the pistons.

The wide number of adjustments of angle, 40 eccentric throw, and of length of eccentric connecting rod, permit of any desired adjustment and timing of the pressure balance or pressure boosting function of the tubular compression piston.

45 The invention, as shown, achieves a volumetric balance at both ends of the stroke when the two pistons are moving in different directions during the period of equal lifts for equal angles.

50 It permits of a lower power stroke, and gives more time for the functioning of the valves, near top and bottom dead center.

When the working piston is at dead center and begins to fall in the cylinder, the tubular compression balance piston rises and balances the pressure above the falling working piston to any desired point. In the diagram this is shown to a point of twenty-two and a half degrees beyond dead center. Then 55

60 the balance piston continues up at a slow rate until it reaches the top of its travel, the working piston, in the meantime, falling rapidly.

By increasing the throw of the eccentrics, 65 greater compression may be obtained, or the

area of the tubular compression piston may be reduced.

By varying the throw of the eccentrics, compression may be made to balance at any desired point with a tubular compression 70 piston of suitable area. The diagram shown is based upon a combination of working piston and tubular compression balance piston, both of equal area.

In the use where the compression is to be 75 increased, after dead center, the tubular piston might be termed a compression boosting piston.

Attention is called to the relatively large 80 range of compression pressures attainable by a relatively small movement of the tubular compression piston after the working piston has come to dead center.

A very small increased movement causes 85 a corresponding decrease in volume, but at the point where this small decrease in volume means a great increase in pressure. That is, after the working piston has passed dead center (the point of maximum compression in ordinary gas engines) by the relatively large angle between the crank and the eccentric, and by adjusting the eccentric throw, and the position and area of the tubular compression piston, I can attain any desired increase in compression. 90

A further and very important new feature 95 is the fact that the up and down movement of the tubular compression piston is much less (about one-half) of the up and down movement as required in my original patent to achieve the required balance on an angle of thirty-six degrees, more or less. 100

I have referred to the operating parts as 105 a crank arm and eccentric, and I would have it distinctly understood that these terms are used in the broadest possible sense to include any mechanical means or mechanism which will function for the purpose, as, for example, the eccentric might constitute a crank arm and other expedients might be resorted to, and I do not wish to be limited to such terminology employed in the specification or the claim. 110

While I have illustrated what I believe 115 to be a preferred embodiment of my invention, it is obvious various changes and alterations might be made in the general form of the parts described without departing from my invention and hence I do not limit myself to the precise details set forth but consider myself at liberty to make such changes and alterations as fairly fall within the spirit and scope of the appended claim. 120

I claim:

In an internal combustion engine, the combination with a cylinder and an auxiliary piston in the cylinder, of a working piston within the auxiliary piston, said auxiliary piston having a displacement within the cylinder such that during the period in which 125 130

the working piston moves from the top dead centre to a predetermined ignition position, the auxiliary piston is given an inward displacement through a portion of its stroke wherein its speed is greatest, the arrangement being such that the product of the area of the auxiliary piston and its displacement maintains a predetermined compression condition.

Signed at New York, in the county of New York and State of New York, this 14th day of November, A. D. 1927.

DOUGLAS J. MARTIN.
